No 1232

U.S. PATENT OFFICE

REED & BROWN

GRANTED APRIL 10, 1860.

President April 10, 1860.

Des. 1232

John Polhamus of New York, N.Y.
Letters Patent No. 1232, dated April 10, 1860,

The schedule referred to in these Letters Patent, and making part of the same.

To all whom it may concern:

Be it known that I, John Polhamus, of the City, County and State of New York, have invented and made or produced a new and ornamental design for striking up or embossing upon the handles of spoons, forks, and articles of Table Cutlery by a die or dies containing such ornamental Design.

And I do hereby declare that the said ornamental design is fully set forth in the following specification, and shown in the accompanying drawing, wherein Fig. 1. is the handle containing said ornamental design as ap-

2

Res. 1232

plied to a spoon, and

Fig. 1. represents the design for the back of the handle, at the junction thereof with the spoon bowl or other article.

The design for the end of the handle is an elliptical shape surrounded with a border of scroll work and scales, pointed ornaments and raised beads are formed on the body of the handle, the whole being represented in Fig. 1.

This ornamental design is to be struck up or embossed and the points and scroll ornaments in Fig. 2. formed at the union of the handle with the bowl, fork, or other article.

What I claim and desire to secure by Letters Patent is the ornamental design to be struck up or embossed upon the handles of Spoons, forks or articles of Table cutlery as described and represented in the drawing.

In witness whereof I have hereunto set my signature this tenth day of March 1860.
